UNITED STATES PATENT OFFICE.

ALBERT MAEULEN, OF INDIANAPOLIS, INDIANA, ASSIGNOR TO ELIAS C. ATKINS, OF SAME PLACE.

SAW TEMPERING AND STRAIGHTENING MACHINE.

SPECIFICATION forming part of Letters Patent No. 363,296, dated May 17, 1887.

Application filed February 23, 1886. Serial No. 192,855. (No model.)

To all whom it may concern:

Be it known that I, ALBERT MAEULEN, of the city of Indianapolis, county of Marion, and State of Indiana, have invented certain new and useful Improvements in Saw Tempering and Straightening Machines, of which the following is a specification.

My said invention relates to that class of machines by which saws are tempered under pressure between parallel surfaces and are thus straightened at the same time; and it consists in the various improvements in such machines, hereinafter particularly described and claimed.

15 Referring to the accompanying drawings, which are made a part hereof, and on which similar letters of reference indicate similar parts, Figure 1 is a view of a machine embodying my said invention, partially in front 20 elevation and partially in longitudinal section, the brick-work which surrounds the machine being omitted; Fig. 2, a transverse vertical sectional view through the machine and the surrounding masonry on the dotted line 2 2 in Fig. 1; Fig. 3, a longitudinal section, on an enlarged scale, of one of the tempering-blocks on the dotted line 3 3 in Fig. 4; and Fig. 4, a transverse section of the same on the dotted line 4 4 in Fig. 3.

30 The machine consists, essentially, of a series of blocks having flat straight surfaces, the upper series of which are held stationary from a supporting upper plate and the lower series of which are supported by a lower plate, one 35 of said series of blocks being adapted to be moved toward the other by a hydraulic or other press, and means for supporting the plates to which these blocks are connected or upon which they rest and of keeping them 40 sufficiently cool to prevent warping, notwithstanding the excessive heat applied directly to said blocks.

It further consists of details of construction in said blocks and the supporting and carrying parts and in a system of dampers for regulating the heat of the blocks severally.

45 In said drawings the portions marked A represent the brick-work or surrounding portion of the furnace; B, columns which extend 50 up and support the upper portion of the machine; C, the upper supporting-plate, to which

the upper tempering-blocks are suspended; D, the lower supporting-plate, carrying the lower tempering-blocks; E E', said upper and lower tempering-blocks, respectively, and F a saw-plate in position as when being operated upon. 55

The masonry A surrounds the operating parts in this machine, as shown, and contains the furnace A', ash-pit A², and flue A³, as well as a pit for the press, all as indicated in Fig. 2. 60

The columns B connect the upper supporting-plate (which also forms the head of the press) to the lower portion of the press, as shown, and, as will be readily understood, receive the strain when the press is put in operation. 65

The supporting-plate C forms the upper portion of the press and also of the machine proper. It has flanges c upon its sides, as shown, which serve as the sides of water-ways, 70 and also large stiffening ribs or flanges C', for the purposes of strength. At numerous points along its center are bosses or projections c', through which the bolts which secure the tempering-blocks thereto pass. These bosses extend above the surface of the water, which flows along over the top of this supporting-plate, and thus prevents the water from entering the bolt-holes. As before indicated, a stream of water is kept flowing over this plate, 75 to keep it sufficiently cool to prevent it from warping or springing. A pipe, p, is shown as leading the water thereto, and a pipe or any other means may be provided for its discharge. The constant flow of water provided by this arrangement is a superior means of effecting this purpose. The strengthening-ribs C' are reinforced by tie-rods c', which extend from the apex of said ribs to the ends of the machine, 80 near where the columns are secured to the plates. They are provided with nuts c' upon their lower ends, as shown, by which any desired degree of strain may be imparted thereto.

The lower plate, D, is of similar construction to the plate C, but of course is reversed in arrangement. A pipe, p', is provided, 95 which conveys the water to the water-way in the surface of this plate provided therefor. Several upwardly-projecting ribs, d, extend up from this plate through the water to the blocks E', which they support, and flanges c, similar in character and purpose to the flanges 100

c on the upper plate, C, are also formed thereon, as shown. This lower or movable portion, D, is provided with trucks or wheels d', which are arranged, as it moves down by the power 5 from the press being released, to rest upon tracks or ways a provided therefor. By this means, by disconnecting this portion D from the press, it can be moved in and out of the furnace, as desired.

16 The blocks E and E' are secured to the plates C and D, respectively, and apertures are formed through said blocks, through which the products of combustion pass from the furnace to the flue. These blocks, as shown most 15 plainly in Fig. 1, are arranged to overlap each other or break joints, and thus serve a better purpose while operating upon the saw-plate than if the joints were one directly above another, thus leaving a portion of the saw-plate 20 wholly exposed. The apertures through these blocks are preferably provided with an asbestos or other equivalent lining, e, which is secured therein (either by a dovetail formation, as shown most plainly in Fig. 3, or otherwise) 25 for the usual purposes of a fire-proof lining.

As will be noticed, particularly by an examination of Fig. 2, one set of the tempering-blocks is provided with a flange which passes by the end of the other and thus shuts off any 30 passage for the products of combustion that might exist between said blocks, and thus keep said products of combustion from direct contact with the saws. Said blocks are also flanged to pass up and down past the 35 corners of the supporting-plates, upon which they are mounted, respectively, for like reasons and purposes, said blocks and also the plates C and D being cut away somewhat to reduce the bearing-surfaces, thus leaving 40 spaces between them, which serve to some extent as air-passages, through which air may circulate and thus assist in keeping said plates C and D cool, the spaces between the upper blocks, E, and plate C being directly between the metal surfaces of said parts, (see 45 particularly Fig. 2,) while the spaces between the blocks E' and plate D are partly occupied with water, and thus the air is between said water and the lower surfaces of said blocks 50 when the water is used as contemplated. While the saw-tempering blocks E are secured to the supporting-plate C by bolts, this is not necessary in the lower blocks, E', which rest upon the supporting-plate D by gravity; but it is 55 necessary to provide some means for preventing them from moving about on their bearings. I have therefore tapered their lower corners somewhat, and inserted between them ribs d', which are secured to the supporting- 60 plate D by bolts, as shown, and these prevent any movement of these tempering-blocks on said plate. Opposite each of the apertures through these blocks in the flue is arranged a damper, E', and by the proper adjustment of 65 these dampers the passage of the products of combustion through the apertures can be con-

trolled, and the tempering-blocks thus maintained at an equal temperature throughout. This flue A³, in which the dampers are located, of course communicates with the chimney or smoke-stack, and thus the required draft is obtained.

The saw-plate F is shown in position between the tempering-blocks, as when being operated upon.

I am aware of the invention of Elias C. Atkins, as shown and described in Letters Patent No. 250,184, dated November 29, 1881, and do not desire to be understood as claiming any of the features of said invention, but 80 only the improvements herein described and claimed.

Having thus fully described my said invention, what I claim as new, and desire to secure by Letters Patent, is—

1. In a saw-tempering apparatus, the combination, with the tempering-blocks, of supporting-plates provided with flanges c' along their edges, whereby a water-way is secured, substantially as shown and described.

2. A supporting-plate, C, provided with flanges c and lugs or bosses c', in combination with the tempering-blocks and a water-supply, said tempering-blocks being secured to said plate by bolts passing through said bosses, substantially as set forth.

3. The combination, in saw-tempering apparatus, of the upper and lower supporting plates or parts and a series of tempering-blocks secured thereto, said blocks being arranged to overlap or break joints, substantially as shown and described, and for the purposes specified.

4. The combination, in a saw-tempering apparatus, of the furnace, the supporting-plates, the tempering-blocks secured to said plates, having apertures therein for the passage of the products of combustion, and dampers E², carried by horizontal rods mounted in bearings in the outer wall and arranged to operate separately in connection with said apertures, substantially as shown and described.

5. The combination, in a saw-tempering apparatus, of the masonry forming surrounding walls, the furnace, the upper and lower supporting-plates, the tempering-blocks secured to said plates, a press for moving one portion toward the other, and dampers supported by horizontally-mounted rods, adapted to be moved toward or from said tempering-blocks and thus to regulate the passage of the products of combustion through the apertures in said tempering-blocks.

6. The combination, in a saw-tempering apparatus, of upper and lower supporting-plates and tempering-blocks secured to each of said plates, one of said blocks being provided with flanges which overlap the other, thus precluding the passage of any of the products of combustion between said blocks, substantially as shown and specified.

7. The combination, in a saw-tempering ap-

paratus, with the movable tempering-blocks, of a supporting part having trucks secured thereto, of a trackway secured to the surrounding walls, whereby as said movable portion is 5 released from the operation of the press it is provided with an independent support, upon which it can be easily handled.

8. In a saw-tempering apparatus, the combination of the series of tempering-blocks and 10 upper and lower supporting-plates, the lower tempering-blocks resting upon the lower one of said plates and secured from moving thereon by ribs d^2 , arranged between them and secured to said plate, substantially as shown and specified.

9. The combination, in a saw-tempering apparatus, of upper and lower plates or parts, tempering-blocks secured thereto, and a suitable press for moving one of said series of 20 blocks toward the other, said upper plate or part being provided with flanges or ribs C' and re-enforcing rods C^2 , substantially as shown and described.

10. The combination, in a saw-tempering apparatus, of upper and lower supporting plates 25 or parts, tempering-blocks having apertures for the passage of the products of combustion

secured thereto, said apertures being lined at their back sides with fire-proof lining e , secured therein, a suitable furnace at one end of 30 said tempering-blocks, and suitable dampers arranged at the other end, whereby the passage of the products of combustion through said apertures may be regulated, substantially as set forth.

11. The combination, in a saw-tempering apparatus, of the upper plate or part, C , having flanges c , forming the side walls of a water-way, tempering-blocks E , secured to said plate or part, a lower supporting plate or part, D , 40 having corresponding flanges, c , forming side walls for a water-way, and projecting portions d , which support the lower tempering-blocks, said lower tempering-blocks E' , and a suitable press, whereby one of said plates or parts and the blocks carried thereby are moved toward the other, substantially as set forth.

In witness whereof I have hereunto set my hand and seal, at Indianapolis, Indiana, this 17th day of February, A. D. 1886.

ALBERT MAEULEN. [I. S.]

In presence of—

C. BRADFORD,

CHARLES L. THURBER.
